UNITED STATES PATENT OFFICE.

JOHN F. ZETKA AND JOSEPH ŠEFČÍK, OF NEWARK, NEW JERSEY.

FIRE-ESCAPE.

1,357,668.

Specification of Letters Patent.

Patented Nov. 2, 1920.

Application filed April 2, 1920. Serial No. 369,864.

To all whom it may concern:

Be it known that we, JOHN F. ZETKA and JOSEPH ŠEFČÍK, citizens of Czechoslovakia, residing at (both) Newark, in the county of Essex and State of New Jersey, have invented certain new and useful Improvements in Fire-Escapes, of which the following is a specification.

The primary object of the invention is the provision of a ready means of escape from burning buildings of any description whereby any number of occupants of the building may quickly reach a place of safety on the ground from an upper window of the building, automatic safety means being employed.

A further object of the invention is to provide a fire escape for upper story windows of buildings so that persons may be carried to the ground easily and quickly the device being automatically controlled and stopped in a cushioned manner preventing injury to the persons escaping from the building.

A still further object of the invention is the provision of means for carrying persons from an elevated position to a point adjacent the ground, the speed of travel being controlled by the passenger and the operation of the device being automatically stopped when the passenger approaches near the ground, the device possessing great strength and adapted for installation upon any kind of building for the escape of the occupants in case of fire.

With these general objects in view the invention consists of the novel combination and arrangement of parts hereinafter more fully described, illustrated in the accompanying drawings, and then claimed.

In the drawings like reference characters designate corresponding parts throughout the several views, and in which—

Figure 1 is a side elevational view of the device operatively mounted upon a building with parts broken away,

Fig. 2 is a front elevation thereof with a part of the chain and basket removed,

Fig. 3 is a sectional elevational view of one of the upper brackets partially broken away,

Fig. 4 is an enlarged elevational view of the journals bearing of one of the upper brackets,

Fig. 5 is an end elevation of the upper portion of the bracket shown in Fig. 3,

Fig. 6 is a side elevation of one of the brake members partially broken away and parts removed,

Fig. 7 is a transverse sectional view thereof,

Fig. 8 is an elevational view of the brake levers and the connections therefor,

Fig. 9 is an elevational view of one of the brake levers,

Fig. 10 is an elevational view of one of the brake linings removed,

Fig. 11 is a transverse sectional view thereof, and

Fig. 12 is two views of one form of the adjustable stop employed for the journal bearings of the upper brackets.

Referring more in detail to the drawings, the device broadly consists of a pair of triangular upper brackets 10 and a pair of similar lower brackets 11 positioned therebeneath secured to the exterior of a building wall as shown in Fig. 1, for mounting endless sprocket chains 13 operatively thereon with a passenger-carrier or basket 14 upon said chains. Rounds or hand-holds, 14' are secured between opposite links of the chains 13 after the manner of a ladder.

The upper sides 15 of the upper brackets 10 are inclined toward the building, and provided with grooves or trackways 16 within which the base 17 of the journal block 18 is slidably mounted. Anti-friction bearings 19 in the trackway 16 for mounting the base 17 thereon cause the blocks 18 to have a tendency to travel by gravity toward the building, it being understood that a shaft 20 is positioned between the blocks 18 through the bushings 21 thereof.

Spaced sprocket wheels 22 are secured upon the shaft 20 inwardly of the journal blocks 18 while brake drums 23 are mounted adjacent the outer free ends of the shaft 20 outwardly of the journal blocks. The lower brackets 11 have journal members 24 depending therefrom with a shaft 25 journaled therethrough for mounting sprocket wheels 26 with the chains 13 substantially vertically positioned over the sprocket wheels 22 and 26.

A side extension 27 at the end of each upper bracket 10 provides a mounting for a cylinder 28 through which a brake rod

29 longitudinally extends. Arcuate sections 30 and 31 encircle each brake drum 23 with linings 32 adapted to frictionally contact the periphery of the inclosed drum. The 5 brake member 30 has a stub shaft 33 adjustably connected to the adjacent end of the rod 29 by a threaded sleeve 34 after the manner of a turn buckle while a link 35 is provided for each brake member pivoted 10 as at 36 to the upper end of the brake member 30 and spanning the outwardly curved end projection 37 of the adjacent member 31 for swinging the member 31 toward the member 30 upon downward movement of 15 the link 35.

A spring 38 between the upper end portions of the brake members 30 and 31 normally tends to hold the brake released from the drum 23 while a roller 39 in each link 20 35 bears upon the outer curved face 40 of the brake ends 37 and a lever 41 projects from each link 35 for convenience in swinging the link downwardly and putting on the brake, a similar brake being provided 25 for each of the brackets 10. The levers 41 thereof are connected together by a rod 42 having a central projecting arm 43 supplied with a downwardly depending cord 44 for convenience in grasping at any point between the upper and lower brackets to set 30 the brakes 30, 31 and retard or stop the movement of the chains 13. An inwardly curved lever 45 pivoted as at 46 adjacent the top of each bracket 11 has a roller 47 in its 35 free end adapted to be contacted by the basket 14 during its descent when a passenger is descending from a point adjacent the upper brackets 10 toward the ground adjacent the lower brackets 11. Springs 40 48 upon the top of the brackets 11 beneath the levers 45 serve as shock absorbers for the basket 14 engaging the rollers 47 while a rod 49 connects the levers 45 together and is provided with an arm 50 to which the 45 lower end of the cord 44 is secured, thereby setting the brakes 30—31 automatically upon the contacting of the basket 14 with said rollers 47. A stop pin 40' through each brake end 37 prevents the link 35 thereof 50 from slipping off of said end.

The basket 14 is collapsible in form and in the operation of the device, persons enter the basket from a point between the upper brackets 10, controlling the downward movement of the basket by means of the cord 44 until the basket engages the rollers 47 automatically setting the brakes 30, 31 and stopping the travel of the basket 14. The person then descends from the basket 60 14 to the ground and the weight of the basket 14 and a similar basket positioned thereabove causes the lower basket to fold up adjacent the chain 13 for passing by the rollers 47, the basket automatically opening therebeneath and assuming its folded pos-

tion when traveling from the lower sprocket wheels 26 to the upper sprocket wheels 22 with the basket upside down. The basket again automatically opens for receiving another passenger between the upper brackets 70 19 it being evident that any number of receiving baskets 14 may be employed which are desirable for the height of the building and the length of the chains 13.

A stud 51 projects from each base 17 75 through the eye 52 of an adjustable stop 53 secured within the trackway 16, a spring 54 surrounding the stud 51 between the base 17 and its adjacently positioned adjustable stop. The sliding of the blocks 18 toward 80 the building is cushioned by the springs 54, it being seen that the weight of a person entering the basket 14 causes the blocks 18 and the shaft 20 to move toward the building.

A spring 55 surrounds each of the rods 29 within its cylinder 28 and bears against the inner end 56 of the cylinder and a shoulder 57 upon the rod 29.

This arrangement also tends to resiliently hold the shaft 20 from sliding toward the building, and tends to prevent the braking action of the brake members 30, 31, when a person enters the basket 14. The upper brackets 10 may be positioned at 95 points on opposite sides of a window so that the occupants of the building may readily enter the basket 14, when the basket is elevated so as to descend safely to a point adjacent the ground in the manner heretofore 100 set forth. The movement of the chains 13 may be continuous if desired by operating either of the shafts 20 or 25.

This fire escape is readily operated by a single person in descending from a great 105 height safely to the ground and by means of the device a building may be quickly emptied of its occupants in case of fire, the same being also serviceable in lowering any form of commodities by means of the basket 14.

While the form of the invention herein set forth is believed preferable, it will be understood that changes may be made therein without departing from the spirit and scope of our invention.

What we claim as new and desire to secure by Letters Patent, is:

1. A fire escape comprising upper and lower pairs of mounting brackets, a shaft transversely journaled beneath the lower 120 pair of brackets, journal blocks anti-frictionally mounted upon the upper pair of brackets, a shaft journaled through said journal blocks, a pair of sprockets upon each of said shafts, endless chains running 125 over said sprockets, passenger-receiving baskets foldably attached to said chains, adjustable resilient stops for the journal blocks, brakes adjacent the ends of the upper shaft outwardly of the journal blocks, resilient 130

positioning connections between said brakes and the upper brackets and controlling means for the brakes adapted for actuation at points between the upper and lower pairs 5 of brackets.

2. A fire escape comprising upper and lower pairs of mounting brackets, a shaft transversely journaled beneath the lower pair of brackets, journal blocks anti-frictionally mounted upon the upper pair of brackets, a shaft journaled through said journal blocks, a pair of sprockets upon each of said shafts, endless chains running over said sprockets, passenger-receiving baskets foldably attached to said chains, adjustable resilient stops for the journal blocks, brakes adjacent the ends of the upper shaft outwardly of the journal blocks, resilient positioning connections between said brakes and the upper brackets, an arm operatively connected to said brakes, shock-absorbing members carried by the lower brackets within the path of travel of the baskets operatively connected to the said brake arm adapted for 25 automatically setting the brakes when the basket reaches a point adjacent the ground during the downward travel thereof.

3. A fire escape comprising brackets adapted to be positioned exteriorly of a 30 building adjacent an upper story window thereof having trackways in the upper side of the brackets inclined toward the building, journal blocks anti-frictionally mounted in said trackways, adjustable resilient stop means for the blocks carried by the brackets within said trackways, a shaft journaled through said blocks and passenger-carrying means operatively carried by said shaft.

4. A fire escape comprising brackets 40 adapted to be positioned exteriorly of a building adjacent an upper story window thereof having trackways in the upper side of the brackets inclined toward the building, journal blocks anti-frictionally mounted 45 in said trackways, adjustable resilient stop means for the blocks carried by the brackets within said trackways, a shaft journaled through said blocks, wheels upon said shaft, endless members over said wheels depending 50 beneath the shaft and a collapsible passenger-carrying basket attached to said endless members.

5. The combination of claim 4, with the following addition:—drums upon said shaft 55 outwardly of the blocks, brake shoe members substantially encircling the drums adapted for frictional engagement therewith, adjustable resilient connections between said brake members at points adjacent the outer free ends of the brackets and operating links for said brake members.

6. The combination called for by claim 5,

with the following addition:—operating levers for said links, an operating arm for said levers and an actuating cord for the 65 arm depending adjacent the building.

7. The combination called for by claim 4, with the following addition:—lower brackets positioned beneath said first-named brackets, a shaft journaled beneath said 70 lower brackets, wheels upon said lower shaft over which said endless members are adapted to travel.

8. The combination called for by claim 5, with the following addition:—lower brackets positioned beneath said first-named brackets, a shaft journaled beneath said 75 lower brackets, wheels upon said lower shaft over which said endless members are adapted to travel.

9. The combination called for by claim 6, with the following addition:—lower brackets positioned beneath said first-named brackets, a shaft journaled beneath said 80 lower brackets, wheels upon said lower shaft over which said endless members are adapted to travel.

10. The combination called for by claim 7, with the following addition:—shock-absorbing arms for the basket pivoted upon 90 the lower brackets in the path of travel of the basket, connections between said arms and the brake cord, the basket adapted for folding subsequent to its engagement with said arms for passing the arms during the 95 continued travel of the endless members and basket during the operation of the device.

11. The combination called for by claim 8, with the following addition:—shock-absorbing arms for the basket pivoted upon 100 the lower brackets in the path of travel of the basket, connections between said arms and the brake cord, the basket adapted for folding subsequent to its engagement with said arms for passing the arms during the 105 continued travel of the endless members and basket during the operation of the device.

12. The combination called for by claim 9, with the following addition:—shock-absorbing arms for the basket pivoted upon 110 the lower brackets in the path of travel of the basket, connections between said last-named arms and the brake cord, the basket adapted for folding subsequent to its engagement with said arms for passing the arms during the continued travel of the endless members and basket during the operation of the device.

In testimony whereof we affix our signatures.

JOHN F. ZETKA
JOSEPH SEFCIK
